UNITED STATES PATENT OFFICE.

WELLINGTON PARKER KIDDER, OF BOSTON, MASSACHUSETTS, ASSIGNOR OF
ONE-THIRD TO CLEMENT B. SMYTH.

TYPE-WRITING MACHINE.

SPECIFICATION forming part of Letters Patent No. 471,795, dated March 29, 1892.

Application filed October 20, 1891. Serial No. 409,340. (No model.)

To all whom it may concern:

Be it known that I, WELLINGTON PARKER KIDDER, of Boston, in the county of Suffolk and State of Massachusetts, have invented a new and useful Improvement in Type-Writing Machines, of which the following is a specification, reference being had to the accompanying drawings, in which—

Figure 1 is a plan of my new type-writer. Fig. 2 is a sectional elevation on line 2 2 of Fig. 1. Fig. 3 is a rear elevation. Fig. 4 is a view showing the ribbon-spools with ribbon removed for greater clearness. Fig. 5 is a detail view of a type-bar in different positions to the guide at the printing-point. Fig. 6 is a perspective view of the rocker-arm which connects each key-lever with its type-bar. Fig. 7 is a perspective of my new panel type-bar. Fig. 8 shows the type-block. Fig. 9 is a diagrammatic view more completely illustrating the type-bar guides and beveled type-block. Fig. 10 is a side view of two sets of guides. Fig. 11 is a plan of the machine with parts removed for greater clearness. Fig. 12 is a top plan of the carriage-supporting mechanism. Fig. 13 shows a modification of the escapement mechanism and connected parts for the endwise feed of the carriage.

My present invention is an improvement upon the type-writer described in my application, Serial No. 386,133, filed March 23, 1891, and allowed September 30, 1891; and it consists in various details of construction, whereby the machine described in the said allowed application is simplified and improved in its construction, operation, and results. These features of my invention are pointed out and claimed hereinafter.

In the drawings, A is the base; B, the key-levers; B', a rocker-arm connecting each key-lever with its corresponding type-bar D, and G is the paper-carriage. The key-levers B are mounted on a cross-bar b, supported in this form of my machine, a cross-rib a, slotted at a to receive the key-levers, and each key-lever engages an arm 1 of the T-shaped rocker-arm B', mounted on a cross-rib a', slotted at a'. The long arm 2 of each rocker-arm B' engages a type-bar D, the bar D being preferably slotted at d to receive the notched end b' of the rocker-arm B'—that is, this is the

preferred form of connecting these parts. The end b' is bent over at an angle and is notched at b² b³, so that one side wall of slot d lies in notch b² and the other side wall of that slot in notch b³.

The type-bars D are mounted in vertical slots a² in rib a², their front ends being between guides a³, supported by the guide-plate a⁴, over which the type-bars slide to deliver impression by end-thrust upon paper on the platen g of the paper-carriage G, which moves endwise in the usual way, while the platen g is movable vertically. A majority of the type-bars support two or more characters each, the characters being arranged one above the other on the front ends of the bars D. The type-blocks D' on the ends of the levers D are each formed with a bevel d' at each end, so that when the type-bar is thrust forward for printing the type-block clears the guide which is opposite the bevel d' and allows side d² of type-block D' to impinge upon side a⁷ of a guide a⁵, so that it is deflected straight to the printing-point. Were the type-blocks not beveled at d' they would be apt to strike against the guide-blocks a⁵ and pass between the guide-blocks with much greater friction than is now the case, owing to the beveling at d'. The beveling is not absolutely essential, the main feature being that the key D is provided with an extension at each end of that part of the type-block on which the characters are, which extension serves as guides. These extensions are shown as parts of the type-block; but it is manifest that they may be integral with bars D, as may also be the type, if preferred. The type-bar-deflecting guides a⁵, between which the type-bars are thrust when impression is taken, are each beveled on their opposed faces at a⁶ and are rigidly secured at the impression-point, the upper pair conveniently on an upright a⁷ and the lower pair on guide-plate a⁴. The type-bars move endwise in paths radiating from the printing-point, and those bars which are at the sides of the bar directly facing the printing-point must be deflected at their type-supporting ends for impression. The type-bars D are necessarily of considerable width to prevent wobbling between the guides a³, but must be as light as possible, and I therefore

form them with openings facing the ribs d^4 , which are at a sufficient distance apart to prevent wabbling and to minimize the weight of the bars. The T-shaped rocker-arm B' forms part of the spacing mechanism II, its arm 3 engaging a cross-bar h , secured to a rocker-arm h' , which is journaled in lugs h^2 of frame A. Rocker-arm h' is provided with a dog h^3 , fast on it, and with a sliding pawl h^4 , mounted on it. The dog and pawl engage a rack h^5 on the paper-carriage. The construction and arrangement of these parts are old and well known and require no further description. Rocker-shaft h' is provided with an arm h^6 , working against the force of a suitable spring h^7 , conveniently mounted, as shown, one of its ends being secured to a part of frame A and its other end to the free end of rocker-arm h^6 .

Inasmuch as the types on a given type-bar are arranged one above the other it is necessary to reciprocate the platen in a vertical path. I accordingly mount platen g in a frame g' , provided with a groove g^2 near its lower edge and extending from end to end of the frame, which slides up and down in vertical guideways g^3 in the endwise-moving section g^4 of carriage G. Those portions of section g^4 which are formed with the guideways g^3 are provided with racks g^5 , with which mesh pinions g^6 , mounted on cross-rod g^7 , journaled in frame g' , the cross-rod g^7 being used to cause the pinions g^6 to travel together and keep the sections of the carriage parallel one to the other. Frame g' is lifted in its ways by a cam-roll g^8 , pivoted on a stud g^9 , fast on a lever g^{10} fast on a rocker-shaft g^{11} , journaled at g^{12} and g^{13} in frame A. The cam-rod g^8 runs in the groove g^2 in frame g' . It is actuated by either of shifting-levers $G' G^2$, mounted on a rocker-shaft g^{14} , journaled at $g^{15} g^{16}$ in frame A. Rocker-shaft g^{14} has arms $g^{17} g^{18}$, arm g^{17} engaging end g^{19} and arm g^{18} engaging end g^{20} of a double lever g^{21} , rigidly mounted on the front end of rocker-shaft g^{11} . At each end of double lever g^{21} a stop g^{22} is arranged to limit the rocking movements of lever g^{21} in each direction. When shifting-lever G' is depressed, cam-roll g^8 is raised through the connections described, carrying with it frame g' , in which the platen is mounted. The cam-roll g^8 is held in one position by the action of a spring g^{23} pressing against a bar g^{24} , which is pivoted to frame A at g^{25} and engages projections g^{26} and g^{27} on lever g^{10} , projection g^{26} being on one side of rocker-shaft g^{11} and projection g^{27} on the other side thereof. Normally, bar g^{24} is in contact with both projections $g^{26} g^{27}$; but when key G' is depressed shaft g^{11} is rocked and projection g^{26} is carried away from the bar, the projection g^{27} being then moved against the bar g^{24} , compressing spring g^{23} . When pressure is taken from key G' , spring g^{23} returns the platen to its normal position. When key G^2 is operated, the motion of lever g^{10} is reversed, as will be plain.

The ink-ribbon I (indicated in dotted lines in Fig. 2) is wound on a spindle j and carried over guide j' , then under guide j^2 , and around j^3 , passing in front of the printing-point between guides j' and j^2 , then returning under guide j^3 , where the returning portion is at the side of the downwardly-moving portion, then over guide j' to a spindle j' , mounted, like spindle j , in cover A' or at any other convenient point. Each spindle carries two disks $j^5 j^6$, between which the ribbon is wound, but only lower disk j^6 is necessary. The spindles are provided with a ratchet-wheel, which is conveniently provided by notching the periphery of disks j^6 . A double pawl J' is pivoted at j^7 between the spindles $j j'$ and is held in contact with one of the ratchet-wheels j^6 by a spring j^8 , which is a bent piece of sheet metal secured to angle-piece j^9 , which is secured to cover A'. (See Fig. 2.) The pawl is actuated to rotate the ratchet-wheel by a rocker-lever j^9 , pivoted to cover A' and connected at its end j^{10} to rod j^{11} , which is loosely pinned at j^{12} to an arm j^{13} of rocker-shaft h' . As the rocker-shaft h' is moved the pawl is actuated. To reverse the movement of the ribbon, the pawl J' is swung into contact with the other ratchet, the spring j^8 holding the pawl in its reversed position after it passes the dead-center.

In Fig. 13, showing a modification, the arm 3 of the rocker-lever B' is a dead part and may be dispensed with, the arm j^{13} from rocker-shaft h' being elongated to hold the cross-bar h over the upper edges of arms 1 of the rocker-lever B' and the dog h^3 being above the sliding pawl h^4 instead of under the sliding pawl, as in Fig. 2.

What I claim is—

1. In a type-writer, a key-lever B, a T-shaped rocker-arm B' , and a type-bar D, in combination with spacing mechanism, the rocker-arm B' being actuated by the key-lever and in turn actuating the type-bar and spacing mechanism, all substantially as described.

2. In a type-writer, the combination of an endwise-moving paper-carriage section g^4 , formed with vertical ways g^3 , a vertically-reciprocating section g' , supporting the platen g , mounted in ways g^3 and formed with a cam-groove g^2 running endwise of it, a cam-roll g^8 , running in said groove and mounted on a rocking lever g^{10} , rocking lever g^{10} , rocker-shaft g^{11} , supporting rocker-lever g^{10} , double lever g^{21} on rocker-shaft g^{11} , rocker-arms $g^{17} g^{18}$ on rocker-shaft g^{14} , each engaging the rocker-lever g^{21} , and shifting-keys $G' G^2$, all substantially as described.

3. In a type-writer, the combination of a series of key-levers, a series of type-bars, a series of levers connecting the key-levers and type-bars, a rocker-arm common to all the connecting-levers, and a spring, all substantially as and for the purpose set forth.

4. In a type-writer, the combination of a key-lever B, rocker-lever B' , endwise-sliding type-bar D, and horizontal guide-plate a^4 , the

rocker-lever B' being intermediate the type-bar D and key-lever B and being directly connected to the type-bar, substantially as shown and described.

5. In a type-writer, the combination of a series of key-levers B, a series of endwise-moving type-bars D, a series of intermediate rocking levers B', and a swinging bar h, connected with a rocker-shaft h', forming part of the spacing mechanism, the bar h being common to all the rocker-levers B', all substantially as and for the purpose set forth.

6. In a type-writer, the combination of a key-lever B with a type-bar D, having an edge slot d, and a rocking lever B', having its end b' at an angle and in the slot d of the type-bar, all substantially as described.

7. In a type-writer, the combination of a platen, an endwise-moving type-bar, a supporting-plate therefor, means for actuating said type-bar, and two pairs of stationary de-

flecting-guides secured to said plate mounted in close proximity to the platen, one pair of the stationary guides receiving and guiding the upper end of the type-block and the other 25 pair of guides receiving and guiding the lower end of the type-block, all substantially as shown.

8. In a type-writer, the combination of a platen, an endwise-sliding type-bar provided 30 with a type-block, a supporting-plate for the type-bar, means for actuating the type-bar, and two pairs of stationary guides secured to the said plate, the type-block being provided with end extensions, each of which is received 35 between a pair of the stationary guides, substantially as and for the purpose set forth.

WELLINGTON PARKER KIDDER.
